UNITED STATES PATENT OFFICE.

ALBERT S. HOWELL, OF CHICAGO, ILLINOIS, ASSIGNOR TO BELL & HOWELL COMPANY, OF CHICAGO, ILLINOIS, A CORPORATION OF ILLINOIS.

STOP AND RECOIL MECHANISM FOR MOTION-PICTURE APPARATUS.

1,237,046.

Specification of Letters Patent. Patented Aug. 14, 1917.

Application filed February 13, 1915. Serial No. 7,932.

To all whom it may concern:

Be it known that I, ALBERT S. HOWELL, a citizen of the United States, and a resident of Chicago, in the county of Cook and State 5 of Illinois, have invented a certain new and useful Improvement in Stop and Recoil Mechanism for Motion-Picture Apparatus, of which the following is a specification.

My invention relates to a stop or brake mechanism for the main driving or power shaft of cinematographic machinery. More particularly my invention has reference to a recoil or cushion device whereby the brake will effectively operate without causing unnecessary jar to the apparatus nor a too sudden stoppage thereof which would place a dislocating and wrecking strain upon the mechanism and upon the film actuated thereby. In the art of cinematography it 15 is often necessary to stop the film actuating shuttle instanter in order to avoid spoiling the film or for other purposes.

My invention is applicable to any mechanism for actuating or moving a ribbon film 25 and I have therefore not shown it as applied to any particular type of mechanism or actuating shuttle.

The principal object of my invention is the provision of means that will cushion 30 the shock incident to the sudden stoppage of the mechanism in order to prevent the parts getting out of adjustment. Another object is the provision of a brake that will stop the mechanism always in a predetermined position relative to the film it is actuating. And further objects are to construct a device of the character mentioned that is effective in operation, easy to manipulate, and economical to manufacture.

I prefer to accomplish the objects of my invention through the means and in the manner hereinafter fully described and as more particularly pointed out in the claims, reference being had to the accompanying 45 drawings, forming a part hereof, in which,

Figure 1 is a vertical longitudinal sectional view of my invention.

Fig. 2 is a transverse vertical section thereof taken on line 2—2, Fig. 1, looking 50 in the direction of the arrows.

Fig. 3 is a sectional view taken on the same vertical plane as Fig. 2 looking in the opposite direction as indicated by the arrows.

55 In the drawings similar reference char-

acters indicate the same parts throughout the various figures. For the purpose of convenience I have not illustrated the particular type of machine to which my invention has been herein applied and have shown the 60 lower portion of the casing 5 thereof that is conveniently provided with a vertically disposed shuttle chamber 6 the lower portion of which communicates with a transversely bored bearing 7 in which the shuttle 65 actuating shaft 8 is journaled. Shaft 8 preferably extends beyond its bearings at its outer end where it is provided with a reduced end portion 9, (the purpose of which will hereinafter more fully appear) and is 70 surrounded by a sleeve or bushing 10 that is coextensive with the thickest portion thereof and which likewise extends outside the bearing 7 the same distance thereas. This bushing is secured in the bearing by a 75 pin α driven through the bearing into the same that prevents its rotation in or accidental removal from said bearing. The inner end of shaft 8 is provided with a disk shaped head 11 carrying a crank pin 12 to 80 which the adjacent lower end of a shuttle actuating pitman or lever (not shown) is mounted.

The outer reduced end portion of shaft 8 is grooved longitudinally to provide a 85 splineway 13 for the purpose of securing one of the members of a friction clutch thereto. This clutch member preferably comprises a hollow sleeve 14 that surrounds the outer end of the shaft 8 and is splined 90 thereto by a key 15 fitting into the splineway 13 above mentioned and is secured to the interior groove of the sleeve by means of a transverse pin 16. The inner end of the sleeve is enlarged to provide a head 17 95 that is cup-shaped and fits over the extended end of the bushing 10 and has a gear 18 formed upon its outer periphery. Secured by pins or otherwise to the outer vertical face of the head is an annular friction ring 19, the central opening of which fits over the inner portion of the sleeve 14. A pulley 20 is mounted loosely on the sleeve 14 the central boss 21 of which is grooved and is adapted to bear against the outer face of 100 the friction ring 19 and is held against the same by any suitable means, preferably the structure herein shown. This structure comprises a friction ring 22 mounted on and rotatable with the sleeve 14 by means of a 105 110

trans-axial headed pin 23, the head of which projects into a longitudinal groove 24 in the outer periphery of said sleeve so as to permit its removal longitudinally therefrom. 5 An expansion spring 25 is coiled around the sleeve 14 between its outer end and said friction ring 22 and is kept under tension by a cup shaped cap 26 mounted upon the outer portion of the sleeve and inclosing said 10 spring.

The pulley 20 is driven by a belt or other means through the medium of a suitable motor and it will be obvious that the pressure exerted by spring 25 will frictionally 15 hold the pulley under ordinary conditions between the friction rings 19 and 22 in order to rotate the latter and through the other instrumentalities will drive the shaft 8 at the same speed as said pulley 20. When, 20 however, the shaft is suddenly stopped the pressure of the spring and the friction of the rings is not sufficient to overcome the momentum of the pulley, the latter will continue to revolve independently thereof between 25 said rings.

I have illustrated one manner of stopping the rotation of shaft 8 which comprises a pin 27 fitted transversely in the head portion of the sleeve so that one end thereof 30 projects beyond the same into the space between said head and the adjacent portion of the supporting frame 5 of the machine. The pulley 20, gear 18 and shaft 8 are adapted to be rotated in the direction indicated by the arrow in Fig. 2 and the two latter elements (the gear and shaft) are adapted to be stopped by means of a suitable reciprocable plunger rod 28 the end of which is movable with the path of said pin 40 27 (Fig. 2). Plunger 28 is mounted in a transverse horizontal bore 29 in the frame of the machine in a plane below and in substantially vertical alignment with the axis of shaft 8 and said plunger is kept normally 45 pressed toward the path of said pin 27 by a coiled expansion spring 30 surrounding said plunger between a collar 31 fixed thereon and a bushing 32 journaling the outer end thereof. A hand grasp 33 is secured to the end of plunger 28 adjacent the spring 30 the central hub of which hand grasp is engaged by the upper arm 34 of a bell-crank lever pivotally mounted below the plunger 28. The free end 35 of the bell-crank carries a metallic disk 36 adapted to be attracted by the core 37 of a magnet 38 when the latter is energized. It is unnecessary to herein discuss the manner or means employed for energizing magnet 38 as the 50 same forms no part of this invention. Suffice it to say, however, that said magnet is in circuit with a contact device engaged by the edge of a standard film which at predetermined points is operated by said film to 55 close the circuit and energize the magnet.

Instantly the magnet becomes energized the disk 36 is attracted to the core thereof thus dropping arm 34 of the bell-crank and permitting the spring to move the plunger to the opposite limit of movement where its 70 opposite end is moved into the path of pin 27. As soon as said pin contacts the end of plunger 28 the rotation of gear 18 and shaft 8 will be stopped and in order to prevent the pin rebounding away from the end of 75 the plunger I mount a spring pressed pawl 39 (Fig. 2) in a recess 40 formed in the face of gear 18. This pawl is kept normally pressed outwardly toward the circumference of the gear 18 by a spring 41 and is provided with a laterally disposed wedge-shaped lug or boss 42 the outer inclined face of which will ride over the end of the plunger and as soon as it has moved past the plunger will again assume its normal 80 position and thereby prevent the rebound of the gear and its connected elements.

In order to cushion or recoil the sudden stoppage of the shaft as just discussed I provide a suitable mechanism which will 90 now be described. A substantially pear-shaped recoil plate or arm 43 has a central opening 44 in its wider portion so that the same may be inserted over the bushing 10 in which shaft 8 is journaled. The bushing 95 is preferably provided with an annular rib 45 that fits into an annular recess 46 cut in said recoil arm around one edge of the opening 44 so that after said arm has been placed upon said bushing it will be held in 100 position by the rib 45. The lower pendent portion of the arm is tapered and its lower end 47 is flattened transversely and is provided with two vertically alining transverse openings 48, 48. These openings afford 105 bearings for the respective ends of oppositely extended horizontal rods 49 and 50 that are prevented from slipping through said openings by nuts or heads 49^a and 50^a on their adjacent ends. The outer ends of 110 said rods are supported in horizontally bored guide bosses 51 and 52 mounted upon the frame of the machine on their respective sides of the arm 43. Nuts 53 and 54 are screwed into the outer ends of these rods 115 for the purpose of adjusting the tension of suitable expansion springs 55 and 56 that are coiled around rods 49 and 50 between the flattened portion 47 of the recoil arm and said adjusting nuts. Suitable adjusting screws 57 and 58 are tapped into the outer opposite ends of the guide lugs 51 and 52 for the purpose of limiting the sliding movement of the rods 49 and 50. An opening 59 is bored through the arm 43 that 120 registers with the bore end of the plunger 28 and through which said plunger is adapted to move to permit its end to engage the pin 27.

From the above it will be seen that as soon 130

as the end of the plunger 28 is engaged by the pin 27 the pawl 39 will prevent the rebound of the same therefrom and at the same time the impact of the moving pin will be imparted to the plunger which in turn transmits it to the recoil arm causing a slight vibratory movement of the latter. The vibration of the arm is cushioned in the one direction and then in the other by the 10 compression and expansion of the springs 55 and 56 thus absorbing the shock caused by the sudden impact of the pin against the end of the plunger. In order to permit of the slight lateral movement that is necessary for the plunger at the moment of contact I prefer to provide a small amount of clearance between the collar 31 thereon and the inner face of the bore and bushing 32 in the end of said bore is slightly tapered internally which has been shown as exaggerated in the drawing.

While I have illustrated and described certain instrumentalities for carrying out my invention it of course will be obvious to others skilled in the art that numerous modifications or refinements thereof are possible without materially departing from the spirit of my invention, and I therefore desire it understood that all such changes are contemplated within the scope of my invention as expressed in the following claims.

Having described my invention, what I claim as new and desire to secure by Letters Patent is:

35 1. A recoil mechanism comprising a shaft, a drive pulley thereon, a friction clutch connecting said shaft and pulley, a lateral member projecting from said clutch, a plunger movable into and out of the path of said member, and a cushioned vibratory arm supporting the adjacent end of said plunger.

40 2. A recoil mechanism comprising a shaft, a drive pulley thereon, a friction clutch connecting said shaft and pulley, a lateral member projecting from said clutch, a plunger movable into and out of the path of said member, a vibratory arm supporting the adjacent end of said plunger, and a cushioning device disposed upon opposite sides of said arm.

45 3. A recoil mechanism comprising a suitable support, a shaft journaled therein and extended beyond its bearings, a drive pulley mounted on the extended end of said shaft, a friction clutch connecting said shaft and pulley, a member carried by said clutch and projecting laterally toward said support, a longitudinally reciprocable plunger journaled in said support and movable into and out of the path of said member, and a cushioned vibratory arm supporting the adjacent end of said plunger.

50 4. A recoil mechanism comprising a suitable support, a shaft journaled therein and extended beyond one of its bearings, a drive

pulley mounted on the extended end of said shaft, a friction clutch connecting said shaft and pulley, a member carried by said clutch and projecting laterally toward said support, a plunger journaled in said support and adapted to be moved into the path of and be engaged by said member, and a cushioned vibratory arm journaled concentrically with said shaft and supporting the adjacent end of said plunger.

5. A recoil mechanism comprising a shaft, a drive pulley thereon, a friction clutch connecting said shaft and pulley, a lateral member projecting from said clutch, a plunger movable into and out of the path of said member, a vibratory arm in which the adjacent end of said plunger is supported, oppositely disposed rods engaging the end of said arm, and springs carried by said rods and bearing on said arm.

6. A recoil mechanism comprising a suitable support, a shaft journaled therein one end of which is extended beyond its bearings, a drive pulley mounted on said shaft, a friction clutch connecting said shaft and pulley, a lateral member rotatable with said shaft, a plunger journaled in said support and adapted to be moved into the path of and be engaged by said member to stop said shaft, and a cushioned arm supporting the end of said plunger adjacent said member.

7. A recoil mechanism comprising a suitable support, a shaft journaled therein one end of which is extended beyond its bearings, a drive pulley mounted on said shaft, a friction clutch connecting said shaft and pulley, a lateral member rotatable with said shaft, a plunger journaled in said support and adapted to be moved into the path of and be engaged by said member to stop said shaft, an arm supporting the end of said plunger adjacent said member, and a cushioning device disposed upon opposite sides of said arm.

8. A recoil mechanism comprising a suitable support, a shaft journaled therein one end of which is extended beyond its bearings, a drive pulley mounted on said shaft, a friction clutch connecting said shaft and pulley, a lateral member rotatable with said shaft, a plunger journaled in said support and adapted to be moved into the path of and be engaged by said member to stop said shaft, an arm supporting the end of said plunger adjacent said member, and a spring engaging the end of said arm.

9. A recoil mechanism comprising a suitable support, a shaft journaled therein one end of which is extended beyond its bearings, a drive pulley mounted on said shaft, a friction clutch connecting said shaft and pulley, a lateral member rotatable with said shaft, a plunger journaled in said support and adapted to be moved into the path of and be engaged by said member to stop said

shaft, an arm supporting the end of said plunger adjacent said member, oppositely disposed rods the adjacent ends of which engage said arm and the opposite ends of which are supported by lugs projecting from said support, and springs surrounding said rods between said lugs and said arm.

10. A recoil mechanism comprising a suitable support, a shaft journaled therein one end of which is extended beyond its bearings, a drive pulley mounted on said shaft, a friction clutch connecting said shaft and pulley, a lateral member rotatable with said shaft, a plunger journaled in said support and adapted to be moved into the path of and be engaged by said member to stop said shaft, an arm supporting the end of said plunger adjacent said member, oppositely disposed rods the adjacent ends of which engage said arm, guide lugs on said support in which the outer ends of said rods are carried, springs surrounding said rods between said arm and said lugs, and means for adjusting the movement of said rods in relation to said lugs.

11. A recoil mechanism comprising a shaft, a drive pulley thereon, a friction

clutch connecting said shaft and pulley, a lateral member projecting from said clutch, a plunger movable into and out of the path of said member, a vibratory arm supporting the adjacent end of said plunger and a cushioning device engaged by said arm.

12. A recoil mechanism comprising a suitable support, a shaft journaled therein one end of which is extended beyond its bearings, a drive pulley mounted on said shaft, a friction clutch connecting said shaft and pulley, a lateral member rotatable with said shaft, a plunger journaled in said support and adapted to be moved into the path of and be engaged by said member to stop said shaft, an arm supporting the end of said plunger adjacent said member, and springs disposed upon opposite sides of said arm and engaging the end thereof.

In witness whereof, I have hereunto set my hand and seal, this 11 day of February, 1915.

ALBERT S. HOWELL. [L. S.]
